DESIGN FOR A FRAME FOR CLOCKS OR SIMILAR ARTICLES

William Frank Day, Albaston, Gunnislake,
England

Application May 17, 1948, Serial No. 146,413
In Great Britain March 4, 1948

Term of patent 14 years

(Cl. D42—7)

To all whom it may concern:

Be it known that I, William Frank Day, a subject of the King of Great Britain, residing at Mayflower House, 3 Gnatton Terrace, Albaston, Gunnislake, in the county of Cornwall, England, have invented a new, original, and ornamental Design for a Frame for Clocks or Similar Articles, of which the following is a specification, reference being had to the accompanying drawing, forming part thereof, and in which drawing:

Fig. 1 is a front perspective view of a frame for clocks or similar articles, showing my new design; and

Fig. 2 is a bottom perspective view thereof.

I claim:

The ornamental design for a frame for clocks or similar articles, substantially as shown.

WILLIAM FRANK DAY.
